CLAIM

The ornamental design for a lid with a straw, as shown and described.

DESCRIPTION

FIG. 1 is a front, right side, top perspective view of a lid with a straw showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, right side, top perspective view thereof showing the carrying handle in a raised position; and,

FIG. 10 is a front, right side, top perspective view of the lid with a straw of FIG. 1 showing the straw feature in a raised position.

The broken lines depict portions of the lid with a straw that form no part of the claimed design.
